(57) **CLAIM**

The ornamental design for a sphygmomanometer, as shown and described.

DESCRIPTION

FIG. 1 is a front perspective view of a first embodiment of a sphygmomanometer showing our new design;

FIG. 2 is a rear perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof;

FIG. 8 is a left side elevational view thereof;

FIG. 9 is a front perspective view thereof with an armband shown in an opened position;

FIG. 10 is a rear perspective view thereof with the armband shown in an opened position;

FIG. 11 is a front elevational view thereof with the armband shown in an opened position;

FIG. 12 is a rear elevational view thereof with the armband shown in an opened position;

FIG. 13 is a top plan view thereof with the armband shown in an opened position;

FIG. 14 is a bottom plan view thereof with the armband shown in an opened position;

FIG. 15 is a right side elevational view thereof with the armband shown in an opened position; and

FIG. 16 is a left side elevational view thereof with the armband shown in an opened position.
